NONRIGID BARGE

William Edmiston Scott, United States Navy

Application January 4, 1943, Serial No. 471,251

7 Claims. (Cl. 114—74)

(Granted under the act of March 3, 1883, as
amended April 30, 1928; 370 O. G. 757)

This invention contemplates the use of non-propelling flexible barges for transporting fluids or other material by water.

The principle involved in the design of these barges is the utilization of the lower specific gravity of the materials to be transported as compared with water to obtain the necessary buoyancy to float the loaded barges. The buoyancy of these barges may be modified so that they can be loaded to the point where the upper surface or deck would be awash, or nearly so without danger to the barges. This feature is important under wartime conditions as it reduces their visibility, especially when viewed from a vessel.

Materials that have a higher specific gravity than water may also be transported by these barges, providing a sufficient amount of air is injected into the cargo hold which is airtight, or into separate airtight chambers to attain the necessary degree of buoyancy. Air injection valves are provided for this purpose. In transporting solid materials it may be necessary to install supporting structures such as a deck and longitudinal and transverse bulkheads to provide solid support for the materials being transported. A barge for this type of service may also require transverse carling beams and watertight cargo hatches of a suitable size.

This type of barge may also be used for storing liquids at desired locations, such as water, gasoline and oil, for fleet facilities, and when used in this manner they may be moored off shore at convenient points.

The objects, in general, are to construct barges of readily available cheap materials that will be adapted for hauling liquids and other materials in a most efficient manner by making them of flexible material, and providing means for floating them in an almost totally submerged condition when loaded, so as to avoid being readily perceived in transport from shipboard of enemy craft. By way of example, one preferred form of the invention is illustrated in the accompanying drawings, it being understood that many changes in form, construction and materials may be made without departing from the scope of the appended claims.

Fig. 1 is a perspective view showing one possible arrangement of towing barges of the type herein disclosed.

Fig. 2 is a side view of one preferred form of the present invention showing a non-rigid barge, the view being shortened by omitting some of the mid sections.

Fig. 3 is a cross section of the barge showing one of the perforated surge baffles that may be used at intervals along the length of the barge.

Fig. 4 is a section on an enlarged scale of one of the manhole rings and covers.

Fig. 5 is a composite top and bottom plan view, shortened like Fig. 2 by omitting some of the mid sections.

Barges of this type may be towed singly or in groups, as illustrated in Fig. 1, or they may be assembled in any combination as desired.

These barges may be made of strips of material 1, running the length of the barge, cut and tailored at their ends to form the rounded forward and stern sections of the barge.

The barges are provided with an air chamber 2 at the forward or towing end that may be charged with sufficient air through the air valve 3 to retain the form of the air chamber or chambers under wave action. This buoyancy chamber would also tend to prevent dipping or nosing under of the barge under rough weather conditions.

The interior compartment 4 aft of the forward buoyancy chamber 2 may be utilized for cargo space and may be provided with transverse water tight bulkheads 5 which may or may not be perforated. If perforated they would merely act as surge baffles and/or reinforcing braces for the envelope.

The materials used in the construction of this barge may be fabric or other material coated on both sides with a selected plastic material, or may be of plastic material without reinforcement.

They may also be made of any other materials of such nature as to provide the necessary air or fluid tightness. The plastics used may be sealable by heat application, cementing, or both, so as to maintain air and fluid tightness, and the outer coating should be insoluble in water and mild acid action, while the interior coating should be insoluble in the liquids to be transported.

The sectional view in Fig. 3 shows one form of perforated surge baffle 5 having cut-out portions at 6. Any desired number and type of bulkheads or baffles may be used along the length of the barge depending on its use and length. The bulkhead at the rear of the air chamber 2 may be shaped as shown in Figs. 2 and 5; the line of the bottom seam of this bulkhead being shown at 21 in the lower portion of Fig. 5 and its top seam at 22 in the upper half of Fig. 5; the rear outline of this chamber is indicated by 23 in Fig. 5. The hull or envelope of the barge may

be reinforced by the application of strips 7 and ribs 7' of heavily reinforced material that is sealed or cemented onto the outer surface of the hull to offset stresses or abrasion that might be encountered under heavy towing conditions. The extremities of these reinforcing ribs and strips may be extended so as to form points of attachments or lugs for towing 8, 8' or lashing 9, 9' as desired. The reinforcing ribs and strips may be reinforced with wire, wire netting or other materials for greater strength.

The upper surface or deck of the barge may be provided with manholes 10, air valves 3, vents 11, inlet pipe 12, and radio controlled lights 14 or other means for navigational purposes. 15 is a reinforced doubling for the manhole mounting, and 16 is a manhole ring which may be made of rigid plastic or other material. The manhole cover 17 may be of reinforced rigid plastic or other material and having a flexible watertight gasket 18; 19 are stud bolts for fastening the manhole covers. 20 is a split metal ring attached to the underside of the hull and having the necessary threaded holes to take the stud bolts to insure air and fluid tightness.

Some of the special features of the above construction of barges to be noted are simplicity of design, speed in construction, availability of materials less essential to the war effort and usability for shallow water transportation, such as rivers, canals or lagoons. The resistance to passage through water in this design of vessel is believed to be considerably reduced by reason of the flexible hull formed, which, when loaded with a liquid conforms to a nearly natural streamlined cross-section throughout the greater part of the length of the vessel. The shape of the cross-section varies according to the water pressure at each point of draft and is dependent on the differential and specific gravity of the fluid being transported and the supporting fluid.

This invention may be used by or for the Government of the United States for governmental purposes without the payment to me of any royalty thereon or therefor.

What I claim is:

1. A non-rigid barge having longitudinal reinforcing strips on its surface to offset stresses or abrasion in use one of said strips being around the lateral periphery of the barge, lashing lugs spaced along the sides of the barge, reinforced

ribs running diagonally from the top and bottom of the barge to said lugs and means for causing the barge to be almost entirely submerged when loaded.

2. A non-rigid barge comprising a water-tight hull of non-rigid material, having longitudinal reinforcing members which are extended at points near the forward and stern ends to form towing plates and diagonal reinforcing members extending at other points along the sides to form lashing lugs.

3. A barge comprising a water-tight envelope of reinforced plastic or fabric material, said material being heavily reinforced by strips and ribs around said envelope extending at points near the ends of the envelope to form towing plates and at points at the sides thereof to form lashing lugs, and means for causing the barge to be almost entirely submerged when loaded and an air chamber in the forward end of envelope for retaining the form of the forward end of the barge under wave action.

4. A barge comprising a water-tight non-rigid envelope, the upper surface or deck having one or more manholes, an air valve for injecting air thereinto of sufficient quantity to just float the envelope when loaded, said envelope having an air compartment in its forward end separated by a water-tight bulkhead from the rest of the space, and means for filling it with sufficient air to retain the form of the forward end of the barge under wave action.

5. A streamlined semi-rigid barge comprising an air-tight hull of non-rigid material having supporting structures of rigid material.

6. A streamlined barge comprising an air-tight hull of non-rigid material having supporting structures of rigid material, an air chamber in the forward end of the hull to furnish buoyancy and to assist the supporting structure in maintaining the streamlined shape of the barge.

7. A streamlined barge comprising an air-tight hull of non-rigid material having supporting structures of rigid material, an air chamber in the forward end of the hull and additional air chambers along the sides of the hull to furnish buoyancy and to assist the supporting structure in maintaining the streamlined shape of the barge.

WILLIAM EDMISTON SCOTT.
